UNITED STATES PATENT OFFICE.

LOUIS W. EISER, OF NOEWOOD, OHIO.

WINDOW.

1,153,208.

Specification of Letters Patent. Patented Sept. 14, 1915.

Application filed February 26, 1915. Serial No. 10,778.

To all whom it may concern:

Be it known that I, LOUIS W. EISER, a citizen of the United States, and a resident of Norwood, in the county of Hamilton and State of Ohio, have invented certain new and useful Improvements in Windows, of which the following is a specification.

My invention relates to window construction; and its object is to construct a window in which the glass may be cleaned on both sides from the inside of and from the floor of the room.

My invention consists in the parts and in the details of construction and arrangement of parts as will hereinafter be more fully described and claimed.

In the drawings, Figure 1 is a plan view of a window casing constructed according to my invention; Fig. 2 is a front elevation of the same; Fig. 3 is a horizontal cross section on a line corresponding with the line $x-x$ of Fig. 2, showing how the upper sash is pulled down and opened through the lower section; Fig. 4 is a vertical section on a line corresponding to the line $y-y$ of Fig. 2, showing another method of using my invention, in which the lower sash is pushed up and the upper sash pulled down and opened under the raised lower sash; and Fig. 5 is a view similar to Fig. 4, showing the lower sash open, while the upper sash is in its normal raised position.

As I prefer to embody my invention, it is combined with a standard window casing having a top 2 and a sill 3 with the upper sash 4 and lower sash 5 sliding up and down in the casing and counterbalanced by weights 6 and 7, respectively, on cords running over pulleys 8 at opposite sides of the window. Preferably, as shown, both sashes 4 and 5 have glass plates 9 and 10, respectively, both of the same dimensions, as is usual in standard window construction; and the sashes meeting at the middle of the window with meeting rails 11 and 12, respectively, properly arranged relative to each other to form an effective closure against the weather. However, each sash 4 and 5 is made in two distinct sections, an outer section 13 and an inner section 14 in the upper sash 4 and an outer section 15 and an inner section 16 in the lower sash 5. The outer section 13 of the upper sash 4 comprises stiles 17 and a top rail 18, while the bottom is formed by a flat relatively thin bar of metal 19 having its ends bent upward and screwed or other-

wise suitably fastened to the lower parts of the stiles 17. The inner section 14 comprises the stiles 21 and top rail 22 and bottom rail 23, thus forming the frame for the glass plate 9; and this entire inner section 14 fits snugly in the outer section 13, abutting against a stop bead 13' which extends in over the inner edges of the outer section 13 to form a weather-tight joint. Hinges 24, at one side, support the inner section 14 on the outer section 13, so that this inner section may be swung horizontally inwardly of the building in which the window is located. The lower edge of the bottom rail 23 of this inner section 14 is rabbeted to fit over the metal bar 19 that forms the bottom of the outer section 14, thus completing the weather-tight joint at the bottom. The outer section 13 has the cords connected to it and to the weights 6, and, with the inner section 14 and its glass plate 9, is thus raised and lowered with all of the facility that an ordinary sash of continuous structure is raised and lowered. Suitable catches 25 at the side opposite from the hinges 24 hold the inner section in closed position in the outer section.

The construction of the lower sash 5 is very similar to that of the upper sash just described except that its arrangement is inverted. Thus, the outer section 15 is made up of stiles 26 and a bottom rail 27 similar to the top rail 18 of the outer section of the upper sash, while the top of the sash is closed, and held rigid by a flat relatively thin metal bar 28 having end parts 29 bent down and screwed or otherwise suitably fastened to the upper parts of the stiles 26, being thus similar to the bottom bar 19 of the upper sash. The inner section 16 is made up of stiles 30, a bottom rail 31 and a top rail 32. These inclose and support the glass plate 10, and the inner section swings horizontally on side hinges 33 in the outer section, abutting against a stop bead 34, and having its top rail 32 rabbeted to fit under and against the top bar 28 of the outer section 15. Suitable catches 35 on the side opposite from the hinges 33 fastened to the inner section in closed position in the outer section. The cords that connect the lower sash to the weights 7 are connected to the outer sides of the outer section.

It will be understood that all of the arrangements for guiding the sashes in their up and down movements and for attaching

the sash cords to the outer sections are after the manner of standard window construction. Also, it is to be understood that the aggregate dimensions of the stiles of the inner and outer sections of either sash, or of the top rail or bottom rail of the upper and lower sashes, respectively, are equal to the standard dimensions of ordinary sashes in which the stiles and top and bottom rails are continuous. It will also be understood that the bottom rail of the inner section of the upper sash and the top rail of the inner section of the lower sash are of the same dimensions as the meeting rails of standard windows; and the only alteration in them is the rabbeting to allow them to pass under and against the respective metal bars that form the bottom of the outer section of the upper sash and the top of the outer section of the lower sash.

A suitable sash lock 36 is mounted on the metal bar 28 of the lower sash and engages with a suitable keeper 37 mounted on the top of the bottom rail of the inner section of the upper sash in the usual manner. To hold the sashes 4 and 5 in any desired positions while they are opened for cleaning the plates 9 and 10, suitable clamps 38 and 39 may be provided at the sides opposite from the hinges, on the casing, inside and outside, respectively, to clamp against the respective sashes.

With the above described construction in a standard window, it is possible to swing the inner section of the lower sash open and then pull down the upper sash and swing its inner section out through the opening in the lower sash, as shown in Fig. 3, thus bringing both sides of both plates 9 and 10 into the room where they may be cleaned on both sides without the necessity of the operator going outside the window, with the danger and inconvenience involved when it is necessary to go on the outside of the window to clean the outer surfaces of the glass plates. In doing this, the cleaning of the plate of the upper sash would be completed first, then the plate would be swung back into the upper sash and the upper sash raised to its normal position, leaving the plate of the lower sash swung inward as shown in Fig. 5, upon which this plate may be cleaned without any obstruction by the part of the upper sash that had been swung inward, and without liability of soiling the plate of this upper sash, due to any accidental splashing or other act while cleaning the plate of the lower sash.

When it may not be desirable to swing the part of the upper sash through the open lower sash, the lower sash may be raised and the upper sash pulled down, and the inner section of the upper sash opened under the raised lower sash, as shown in Fig. 4. To permit this without involving the ne-

cessity of making the plates of the sashes of unequal size and of correspondingly varying dimensions of the two sashes, I provide the top 2 of the window casing with an opening 40 that will allow the upper part of the lower sash to project up through it any distance necessary to leave a proper opening below the raised lower sash for swinging the inner section of the lowered upper sash inward. To normally close this opening 40 against dust and other matter which may fall down from the interior of the wall of the building into the window opening, I provide a plug 41 in the form of a strip of length and width to fit neatly in the opening 40, and preferably of the same thickness as the top 2 of the casing, thus making this top 2 practically continuous at all times except when the lower sash is to be raised through it. The ends of this plug 41 may have recesses 42, and suitable vertical guides 43 are secured in the ends of the opening 40 and are received in the recesses 42 in the end of the plug 41 so that the plug is guided in its up and down movement in such a manner that it will always come back into its correct position in the opening under the action of gravity as the lower sash is pulled downward out of the opening 40. Stops 44 extend laterally from the upper side of the plug 41 and engage with the upper side of the top 2, limiting the downward movement of the plug. As here shown, the vertical guides 43 are thin strips which extend some distance down in the interior of the window casing and are received in the grooves 45 in the sides of the lower sash, which grooves are provided as usual for the application of the sash cords to the sash. By this means, providing a passage for the upper part of the lower sash up through the top of the casing it will be seen that extensive alteration of the casing is rendered unnecessary, while at the same time permitting the full operation of the sectional sashes for the purpose of my invention without the necessity of varying any of the dimensions of the ordinary standard sashes. However, I prefer the means first described, involving the provision of the lower sash with the top of the outer section made up of the thin flat horizontal bar, which leaves the interior opening of the lower sash so large that the upper inner section, when the upper sash is brought down, may swing through this opening, and yet so that the top of the lower sash will not extend up so high as to vary from the standard arrangement of meeting-rails of the sashes. This construction, while thus allowing the glass plates of the two sashes to be of the same dimensions and allowing the entire window construction to be standard, does not involve the cutting away of any part of the window 130

casing as in the second example above described. Furthermore, it is not only possible to open the inner section of the upper sash through the outer section of the lower sash when the two sashes are at the bottom of the window, to facilitate cleaning, but this relative operation of the two sashes may be accomplished when both are at the top of the window, with a decided advantage in increasing the ventilation. It is thus possible to have the entire window open practically from the top to the bottom, as is highly desirable in hot weather, and at the same time to depart very little from the ordinary standard window construction. The same arrangement at the bottom of the upper outer section permits of a standard meeting-rail without undue bulk at the bottom of the upper sash.

With my invention, it will be found possible not only to provide new buildings with my improved sashes, but to alter the sashes of windows already constructed and installed, to operate in the manner desired, without the necessity of constructing new sashes; and even where it may be desirable to construct new sashes made up of a plurality of sections, it will be seen that no prohibitive alterations are required. Any alteration in the window casing that involves disturbing the exterior woodwork thereof, either in the inside of the room or on the outside of the house, is virtually prohibitive, because it would practically involve reconstruction of the window. The ease with which my invention is installed in completed buildings therefore, makes it possible to extend the undoubted benefits of this method of constructing and cleaning windows much farther than would be practically possible with a structure involving much alteration and renewal, because of the reluctance of building owners to incur expense of such an excessive change in construction; whereas, with my invention, the moderate changes required are not likely to meet with so much opposition from those who must bear the expense of the alterations.

Having fully described my invention, what I claim as new and desire to secure by Letters Patent is:

1. In a window, a casing, an upper sash comprising an outer section sliding up and down in the casing, and an inner section hinged to and swinging into and out of the outer section, a lower sash sliding up and down in the casing inwardly of the casing from the upper sash, and comprising an outer section and an inner section hinged to and swinging into and out of the outer section, said outer section of the upper sash comprising stiles, and a top rail and a bottom member rigidly joining the stiles across the window, the inner section of said upper sash comprising side rails and a top rail

and a bottom rail of shape and dimensions adapted when fitting into the opening inclosed by the outer section to make up a sash of standard dimensions, a transparent plate held in the stiles and rails of the inner section, said outer section of the lower sash comprising stiles and a bottom rail, and comprising a flat relatively thin top bar of metal rigidly securing the upper parts of the stiles together across the window, and said inner section of the lower sash comprising stiles and a bottom rail and a top rail, said stiles and rails of the inner section being of shape and dimension such that when they are inclosed by the outer section they will make up, with the respective stiles and rails and the bar of the outer section, a sash of standard dimensions, and a transparent plate held in the stiles and rails of the inner section.

2. In a window, a casing, an upper sash comprising an outer section sliding up and down in the casing, and an inner section hinged to and swinging into and out of the outer section, a lower sash sliding up and down in the casing inwardly of the casing from the upper sash, and comprising an outer section and an inner section hinged to and swinging into and out of the outer section, said outer section of the upper sash comprising stiles and a top rail, and a flat relatively thin bottom bar of metal rigidly joining the lower parts of the stiles across the window, the inner section of said upper sash comprising stiles and a top rail and a bottom rail of shape and dimensions adapted when fitting into the opening inclosed by the outer section to make up a sash of standard dimensions, a transparent plate held in the stiles and rails of the inner section, said outer section of the lower sash comprising stiles and a bottom rail, and comprising a flat relatively thin top bar of metal rigidly securing the upper parts of the stiles together across the window, and said inner section of the lower sash comprising side rails and a bottom rail and a top rail, stiles of the inner section being of shape and dimension such that when they are inclosed by the outer section they will make up, with the respective stiles and rails and the bar of the outer section, a sash of standard dimensions, and a transparent plate held in the stiles and rails of the inner section.

3. In a window, a casing, an upper sash comprising an outer section sliding up and down in the casing, and an inner section hinged to and swinging into and out of the outer section, a lower sash sliding up and down in the casing inwardly of the casing from the upper sash and comprising an outer section and an inner section hinged to and swinging out of the outer section, said inner section of the upper sash having its bottom composed of a meeting rail, and

- said inner section of the lower sash having its top composed of a meeting rail, said meeting rails coöperating by engagement of their upright sides together when the upper sash is up and the lower sash is down, and a transparent plate in each of said inner sections, the top of said outer section of the lower sash being composed of a flat relatively thin bar of metal extending across 10 above the meeting rail that forms the top of the inner section of the lower sash, and allowing said meeting rail to swing under this bar and coöperate with the meeting rail of the upper sash, as aforesaid.
- 15 4. In a window, a casing, an upper sash comprising an outer section sliding up and down in the casing, and an inner section hinged to and swinging into and out of the outer section, a lower sash sliding up 20 and down in the casing inwardly of the casing from the upper sash and comprising an outer section, and an inner section hinged to and swinging out of the outer section, said inner section of the upper sash having
- its bottom composed of a meeting rail, and 25 said inner section of the lower sash having its top composed of a meeting rail, said meeting rails coöperating by engagement of their upright sides together when the upper sash is up and the lower sash is down, and 30 a transparent plate in each of said inner sections, the top of said outer section of the lower sash being composed of a flat relatively thin bar of metal extending across 35 above the meeting rail that forms the top of the inner section of the lower sash, and allowing said meeting rail to swing under this bar and coöperate with the meeting rail of the upper sash, as aforesaid, the upper side of said meeting rail forming the top 40 of the inner section being rabbeted and leaving an inner part projecting up alongside the inner edge of said flat bar, for the purposes set forth.

LOUIS W. EISER.
